United States Patent Office.

H. S. PALMER, OF NORVELL, MICHIGAN.

Letters Patent No. 64,697, dated May 14, 1867.

IMPROVEMENT IN MANURE-DISTRIBUTOR.

The Schedule referred to in these Letters Patent and making part of the same.

TO ALL WHOM IT MAY CONCERN:

Be it known that I, H. S. PALMER, of Norvell, Jackson county, State of Michigan, have invented certain new and useful Improvements in Machines for Sowing Manures: and I declare the following to be a full, true, and exact description of the same, reference being had to the accompanying drawings, which form a part of these specifications, and the letters of reference marked thereon.

Figure 1 represents a plan view of the machine.

Figure 2 represents a side view of the same.

Letter A represents the box of the machine into which the lime, plaster, bone-dust, or other manure is placed for the purpose of being sowed broadcast over the field. Attached to the rear side of the box A are two metallic hooks, B B, for the purpose of suspending and supporting the box while attached to the wagon or cart. Letters D D represent two braces, the lower ends of which are secured to the rear side of the box A by the rod C so as to allow them a reciprocating motion, while the upper ends come in contact with the lower side of the wagon box immediately back of the axle-tree. These braces are provided for the purpose of steadyng the box A, and to prevent it from swaying backwards and forwards. To give the braces greater strength and security the cross-tie E is provided, which passes through both braces, thus forming them firmly and securely together. In order to prevent the braces D D from slipping from their places under the wagon box, the strap or chain F is added, which passes round the axle-tree and through the cross-tie E; it is then drawn tight, and the braces are firmly held, and the box is prevented from either swaying or jarring when the vehicle to which it is attached is set in motion. Attached to the bottom of the box A is the frame or board G, which is so hinged to the bottom as to allow it an upward and downward stroke when the wagon is in motion. Letter H represents a cam pulley, which is attached to the same side of the box A as the braces D D, and is used for the purpose of communicating the up and downward stroke to the hinged board G by means of the arm or rod I, the upper end of which bears against the cam pulley, while the lower one is attached to the board G. As soon as the pulley is set in motion, the arm I is pressed back from the box, as shown in fig. 1, and then suddenly released, which causes it to fly back, thus setting the board G in motion. Attached to the board G is a series of wires which work through the slot in the bottom of box A. These wires or teeth J may be set in an angular manner or made serpentine, and are used to force the manure through the slot, from whence it falls to the earth. The up and downward stroke of the board or frame G is communicated to the wires or teeth, which catch the manure on their under side and force it downward. The cam pulley H is so adjusted that it can be moved nearer to or further from the fulcrum, thereby regulating the discharge of the manure from the box by altering the stroke of the teeth. In order to set the cam pulley in motion, a band pulley or smaller wheel is fastened to the main wheel of the wagon or cart. A strap or cord passes around both pulleys, so that when the main wheel begins to revolve it sets the two pulleys in motion.

The advantages of my machine are, it can be attached to any kind of a vehicle, or can be made with wheels of its own. The discharge of the manure can be regulated at pleasure, and will sow one kind of a manure almost as well as another.

Having thus described my invention, what I claim, and desire to secure by Letters Patent, is—

1. The cam pulley H, the arm I, and the hinged board or frame G, when constructed and operating in the manner and for the purpose as herein specified.
2. The cam pulley H in combination with the arm I, when so constructed that the pulley can be moved nearer to or further from the fulcrum, whereby the discharge may be regulated by altering the stroke of the teeth J.
3. The hooks B B, the braces D D, and the strap or chain F, in combination, when arranged and constructed as herein specified.

In testimony that I claim the foregoing as my own I hereby affix my name in the presence of two witnesses.

H. S. PALMER.
